UNWINDING APPARATUS FOR PAPER WEBS
AND THE LIKEAdolph Potdevin, Garden City, N. Y., assignor
to Potdevin Machine Company, Brooklyn, N. Y.,
a corporation of New York

Application October 8, 1935, Serial No. 44,000

1 Claim. (Cl. 242—75)

In all types of machines utilizing continuous webs wound in rolls, it is necessary or desirable in drawing the web from the roll by constant speed mechanism, such as positively driven friction forwarding rolls, that the tension on the web be kept constant.

It will be understood that in unwinding the web from a roll by constant speed mechanism, where a friction device is employed contacting with the periphery of the roll being unwound, that the friction applied to the roll must be greater at the beginning of the unwinding operation than at the end of the operation, this friction decreasing in direct proportion to decrease in the diameter of the roll. This is taken care of automatically in the present invention.

I also provide in the machine of this application for varying the applied friction initially so as to accommodate the machine to various widths 20 of web and different materials.

In the accompanying drawing:

Fig. 1 is a side view of a machine embodying my invention with the parts in position with a full roll of paper;

Fig. 2 is a similar view but with the roll of paper nearly depleted; and

Fig. 3 is a plan view of the showing of Fig. 1.

Referring more particularly to the drawing, 1 designates the roll of paper which is to be unwound, this roll being supported on shaft 2 which in turn is supported in bearings in the two side frames 3 and 4 of the machine.

Contacting the periphery of the roll of paper 1 is a belt 5 removably secured at one end to a 35 bar 6 supported in uprights 6', the bar being located above the roll 1 and extending lengthwise thereof. The other end of the belt is made fast to a drum 7 which is mounted on a shaft 8, supported in suitable bearings on the side frames 3 and 4, this drum being positioned below and slightly to one side of the roll. The shaft 8 carries a gear 9 which meshes with a gear 10 fixed to shaft 11.

Affixed to the shaft 11 is an arm 12 which 45 carries a weight 13. The weight 13 is adjustable along the arm toward and away from the shaft 11. Affixed to the shaft 11 and projecting from the shaft at the side opposite the arm 12 is another arm 14 which is used to hold the arm 12 and weight 13 vertical while installing the paper roll.

In setting up the machine the weight 13 and arm 12 are moved to a vertical position or slightly to the left of vertical, and held in that position 55 by the arm 14 striking the machine frame and the upper end of the belt 5 unhooked from the shaft 6. The full roll 1 may now be placed in position, the belt 5 passed about the periphery of the roll and its upper end again secured to 60 the shaft 6.

Inasmuch as with a full roll the distance from the center of the roll to the point where the web is leaving the roll is greatest, it will be apparent that at this time the pressure of the belt 5 on the face or periphery of the roll should be greatest. 5 Accordingly the arm 12 and weight 13 are rotated clockwise to position where the arm is horizontal, thus attaining the greatest leverage from the pull of gravity. The weight 13 is then adjusted along the arm 12 until the desired pressure is 10 produced on the periphery of the roll to give the desired tension in the web as it is unwound. It will be evident that as the web is drawn off the roll and the virtual diameter of the roll decreases, the weight 13 will gradually lower and at the 15 same time the belt 5 will be wound upon the drum 7, the latter rotating in an anti-clockwise direction through the gears 9 and 10 as the weight descends. Inasmuch as the weight 13 exerts its maximum pull on the belt 5 when the 20 arm 12 is horizontal, it will be evident that the pull on the belt will decrease uniformly as the weight descends to decrease the pressure on the periphery of the roll 1, and this action in conjunction with the ratio between the gears 9 25 and 10 is such that the pressure of the belt on the roll periphery will decrease in direct proportion to the reduction in the virtual diameter of the roll 1 due to the unwinding of the web, that is, in direct proportion to the reduction in 30 the length of the lever arm represented by the distance from the center of the roll 1 to the point where the web leaves the roll. It will be apparent, therefore, that when this lever arm is 35 shortest, i. e., when practically all of the paper has been unwound the pressure of the belt 5 on the periphery of the roll is at a minimum.

What I claim is:—

Unwinding apparatus for rolls of strip material, 40 comprising in combination a frame, means for rotatably supporting a roll to be unwound on said frame, a belt having one end anchored to said frame above said roll and passing about the roll and contacting the periphery thereof, a drum 45 having the other end of said belt secured thereto, a weight, a lever on which said weight is adjustably mounted, a gear for gearing said lever to said drum, said weight swinging in an arc by gravity concentric with said gear as the 50 roll is unwound to wind the belt on said drum thereby uniformly to decrease the contact pressure of the belt on the roll periphery in direct proportion to the uniform reduction in the virtual diameter of the roll as unwinding proceeds, 55 whereby maximum belt pressure is applied to the roll periphery when the roll diameter is maximum and minimum belt pressure when the roll diameter is minimum.

ADOLPH POTDEVIN. 60
